COVER FOR BED-FORMING STRUCTURES

Immacolata Pisciotta, New York, N. Y.

Application July 10, 1944, Serial No. 544,218

9 Claims. (Cl. 5—354)

1

This invention relates to covers for bed-forming structures.

The invention has been entitled, and will be described and illustrated, in connection with a mattress. However, it will be understood that the phrase, bed-forming structure, as used herein, is not intended to be limiting, as the invention may have application in connection with structures other than mattresses, as, for instance, bed springs and like structures requiring covering and accessibility of parts of the structure covered.

Bed-forming structures such as mattresses generally are provided with ventilation openings, straps or similar devices to which access, during the use of such structures, must be possible with great ease. In order to prevent penetration of dust into the body of such a structure, it has generally been recognized as desirable to cover such structures during their use on beds or the like; covers made from materials such as the textiles are used, and thereby ventilation openings, straps and the like are made relatively accessible.

In this connection, it is noted that the term, "access requiring means," as used herein, is intended to refer to devices such as the ventilation openings, straps, and manipulating means, generally associated with bed-forming structures such as mattresses and requiring access during the time the structures are encased in the covers.

It is an object of the invention to provide a cover for a bed-forming structure, wherein accessibility for ventilation openings, straps or the like, is provided without substantial interference with the shielding function of the cover. The cover is so constructed that, by a simple manipulation, and without disturbing the relation of the cover to the structure, access to the covered parts may be had immediately. On the other hand, unless such manipulation takes place, so that, for instance, the hand may be inserted to grasp the strap or to perform some other operation, the structure remains sealed substantially positively and completely within the cover.

Other objects of the invention will be set forth hereinafter, or will be apparent from the description and the drawings, in which are illustrated embodiments exemplifying the invention.

On the drawings, in which the same reference characters refer to the same parts throughout, and in which are disclosed such operative embodiments,

Fig. 1 is a perspective view showing a portion of a bed having a mattress disposed thereon, and a cover for the mattress embodying features of the invention, the mattress and the cover being broken away;

Fig. 2 is a perspective view of the cover for a mattress shown in Fig. 1 to a reduced scale;

Fig. 3 is a perspective view to an enlarged scale of a modified form of mattress cover, the cover

2

being broken away in sections, and one flap being shown partially open;

Fig. 4 is a view similar to Fig. 3 of another modified form of mattress cover; and

Fig. 5 is a side elevational view of a further modified mattress cover, one of the flaps being broken away to illustrate the construction.

On the drawings, the invention has been illustrated in connection with a mattress 10 shown disposed upon the cross-bars 12 of a bed 14 (shown only in part). Mattress 10 is shown in the usual form; it is illustrated as having a pair of straps 16 at each side wall 18. These straps facilitate handling of the mattress when it is to be placed in position, or is to be removed from position, as, for instance, upon cross-bars 12. While straps 16 have been illustrated as attached to side walls 18, their location or relation to the mattress may be determined by specific requirements; thus, the association may be with any of the walls, faces or other structural parts, as, for instance, with the end walls, or with bottom 22, or top 24. Cover 26 is constructed to coordinate with a particular arrangement of a device or devices upon any one or more walls of a particular mattress.

Straps 16 are being located upon the walls of a mattress at positions which, as time goes on, are arriving at a substantially standardized construction. The dimensioning of a mattress, the distance between straps, and the particular locations of the straps upon a side wall, an end wall, the top or the bottom—all of these have become substantially standard. Thus, in the case of cover 26 here to be described, it may be assumed that, when such a cover is assembled upon the mattress, the dimensioning of the cover and its several parts automatically will result in locating the parts of the cover with relation to related parts of the mattress.

Cover 26 itself may be fabricated from any desired material. For instance, a suitable textile, which may be waterproofed or not, as desired, may be utilized. In any case, the cover may comprise top and bottom panels 28 and 30, end panels 32 and side panels 34. These panels may be secured together for defining the contours of the cover, as, for instance, by stitching along contiguous edges. Thus the cover will be caused to assume a shape substantially the same as that of the mattress itself. The panels may be solid in extent, that is, without any break, or, as desired, they may be pieced out of sections of such material.

In the particular structure disclosed, straps 16 on the mattress are shown disposed on side walls 18 so that they are covered by side panels 34. As shown, the straps may consist of a length of fabric similar to that from which the mattress is formed. This fabric may be folded to define the straps,

and the straps so formed are then secured to the mattress by being stitched together with the fabric of the mattress at the bottom edges 36 of side walls 18.

In Figs. 1 and 2, each of side panels 34 of cover 26, located with relation to side walls 18 and associated straps 16, is constructed from a plurality of sections of material. For instance, a side panel 34 may consist of sections 38, 40 and 42. These sections are located between and are stitched to top and bottom panels 28 and 30, respectively. In constructing a cover 26 from this material, edges 44 and 46 of sections 38 and 42 may first be stitched to edge 48 of top panel 28, ends 50 and 52 of sections 38 and 42, respectively, being first positioned to coincide with the respective corners 54 and 56 of top panel 28. Then section 40 is positioned so that its end edges 58 extend beyond and overlie end edges 60 and 62 of sections 38 and 42. In other words, section 40 overlaps sections 38 and 42, and its end edges 58 are outside and cover end edges 60 and 62. In this relationship, section 40 is stitched to edge 48 of top panel 28, and also to those portions of edges 44 and 46 which have already been stitched to edge 48.

Now that sections 38, 40 and 42 have been assembled with top panel 28, bottom panel 30 is brought into association with bottom edges 64, 66 and 68 of sections 38, 40 and 42, respectively. A single stitching operation will be sufficient to secure the sections and bottom panel together. Then the completion of the cover may follow by stitching the necessary end panels 32 to side panels 34 and top and bottom panels 28 and 30.

It will be noticed, as shown in Fig. 1, that merely by pushing an edge 58 laterally towards its associated edge 60 or edge 62, an opening is provided through which access may be had to a strap 16 positioned adjacent to that opening. Immediately upon release of that edge 58, the fabric snaps back into position by the tension imparted by the mattress, the opening is closed, and the edges become tightly overlapped to prevent entrance of dust within the cover.

In Fig. 3, another panel construction 70 is illustrated. Panel construction 70 includes a pair of sections 72 and 74. The sections may be substantially identical with each other except, for instance, that panel 72 is the counterpart or mirror image of panel 74. Thus, while they could be superimposed, their parts would be positioned in identical relation only by reversing one of the panels with relation to the other. In this case, sections 72 and 74 have openings 76 and 78 formed immediately adjacent their respective edges 80 and 82, and extending a considerable distance away from those edges.

Sections 72 and 74 are first assembled with section 84. The total of the lengths of panels 72, 74 and 84 is greater than the extent of panels 86 and 88 to which panel construction 70 is to be united. Thus, in effecting assembly of panels 72, 74 and 84 to define construction 70, panels 72 and 74 are laid down so that their extreme edges 90 and 92 are spaced apart sufficiently so that, in the final assembly, they will coincide with edges 94 and 96 of panels 86 and 88. Now edges 80 and 82 face each other. Section 84 is now superimposed upon sections 72 and 74 so that edges 98 and 100 of section 84 extend beyond edges 80 and 82, and overlap sections 72 and 74.

Extending flaps 102 are thus defined by edges 98 and 100. The amount of overlapping of section 84 over each of sections 72 and 74 is greater than the extent of openings 76 and 78. Section 84 is

stitched to sections 72 and 74 by seams 104 which engage through the small strips 106 between openings 76 and 78 and the respective edges 80 and 82 of said sections, and through the body of section 84 immediately above strips 106.

Sections 72, 74 and 84 are secured together as a single panel construction 70. Each of these panel constructions may now be stitched, as a single operation, to panels 86 and 88.

Suitable snap fasteners 108 may be provided around the borders of the free edges of flaps 102 and the coincident portions of sections 72 and 74 so that the flaps may be secured in position to guard openings 76 and 78. When snap fasteners 108 are released, access is had, by swinging flaps 102 away, to the particular device beneath the particular flap.

In Fig. 4, a modified panel construction 110 is illustrated. Panel construction 110 includes sections 112 and 114 which are substantially rectangular at ends 116 and 118. Another section 120 is provided with incut portions 122 at its end edges 124 and 126. Sections 112, 114 and 120 may be disposed in the same manner as sections 72, 74 and 84, but now ends 116 and 118 of sections 112 and 114 overlap ends 124 and 126 of section 120 to the extent that incut portions 122 are covered completely. Stitching along lines 127, catching through both layers where superimposed, but catching only through the single layer at the gap, serves to couple the sections together to form panel construction 110.

Then panel construction 110, thus formed from sections 112, 114 and 120, may be stitched, along the single edges 128 and 130, thus defined, to the related top and bottom panels 132 and 134. Then suitable snap fasteners may be provided around the boundaries of laps 136 and the edge portions of section 120 where they are overlapped and left free, so that free access to the openings provided by incut portion 122 will follow.

Another panel construction 138 is illustrated in Fig. 5. In this case, sections 140 and 142 are substantially identical in construction except that they are mirror counterparts. At end edges 144 and 146, respectively, cut-outs 148 are formed, leaving gaps, and wings 150. Section 152 has its ends 154 cut away to leave laps 160. Sections 140 and 142 are arranged to assume the end positions of panel construction 138. Section 152 is superimposed on the positioned sections 140 and 142 so that, even as cut away, ends 154 will overlap edges 144 and 146, while laps 160 will cover the gaps formed by cut-outs 148. Lines of stitching 162 may then secure section 152 to sections 140 and 142 at the superimposed portions immediately adjacent ends 154 and edges 144 and 146. Suitable snap fasteners 164 may be associated with the free edges of laps 160 and cut-outs 148.

Many other changes could be effected in the particular constructions, and in the methods of use and construction, and in specific details thereof, hereinbefore set forth, without substantially departing from the invention defined in the claims, the specific description being merely of embodiments capable of illustrating certain principles of the invention.

What is claimed as new and useful is:

1. A cover for a bed-forming structure, wherein means requiring access thereto from a position externally of the structure are provided for certain of the walls of the structure, and wherein the access requiring means are secured to and

extend from certain walls of the structure, the cover comprising a plurality of panels forming top, bottom, end and side walls, the panels being dimensioned to be substantially coextensive with the walls of the structure and being stitched together along substantially contiguous edges, the panel for positioning at the locality of the access requiring means being constructed to define means for providing access to the access requiring means, the panel comprising a plurality of sections, the total length of the sections being greater than the length of the panel, but the sections being overlapped, one of the sections having a portion cut away substantially immediately at the position of the access requiring means, and that section of the panel and the immediately contiguous overlapped section being secured together so that the immediately contiguous section provides a flap extending freely over and forming a covering for the opening provided by the cut away portion, and means for releasably retaining the flap to close the opening.

2. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a plurality of sections, one of the sections of that panel having an opening provided therein, the sections of that panel being overlapped so that another of the sections overlaps the opening, and the section having the opening and the other section overlapping the opening being secured to each other so that the overlapping section has a free end, the free end being movable to permit access through the opening for engaging the associated device.

3. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a plurality of sections, the end of one of the sections of that panel having a cut-back formed therein, the sections of that panel being overlapped so that another of the sections overlaps the entire cut-back, and the section of that panel having the cut-back and the section overlapping the cut-back being secured to each other so that the overlapping section has a portion thereof forming a free flap to provide access through the cut-back to the associated device.

4. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last

mentioned panel including a plurality of sections, the end of one of the sections of that panel being cut away in part to leave extending therefrom at least one wing of a width less than the width of the section, the sections of that panel being positioned one upon the other so that another of the sections forms a lap extending at least to the innermost extremity of the wing, and the section of that panel having the wing and the section having the lap being secured to each other so that the lap has a free end, the free end being movable to permit access to the associated device through the cut away portion of the section.

5. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a plurality of sections, the end of one of the sections of that panel being cut away in part to leave extending therefrom at least one wing of a width less than the width of the section, the sections of that panel being positioned one upon the other so that another of the sections forms a lap extending at least to the innermost extremity of the wing, and the section of that panel having the wing and the section having the lap being secured to each other along a line common with the extremity of the wing and the body of the lap so that the lap has a free end, the free end being movable to permit access to the associated device through the cut away portion of the section.

40 6. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a pair of sections, the end of one of the sections of that panel being cut away in part to leave a pair of wings extending therefrom and having a gap therebetween, the pair of sections being positioned one upon the other so that the other section forms a lap extending at least to the innermost extremities of the wings, and the pair of sections being secured to each other along a line common with the extremities of the wings and the body of the lap so that the lap has a free end, the free end being movable to permit access through the gap to the associated device.

65 7. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a pair of sections, the end of one of the pair of sections being cut away in part to leave a pair of wings extending therefrom

and having a gap therebetween, the sections of that pair being positioned one upon the other so that the other section of the pair forms a lap extending at least to the innermost extremities of the wings, and the sections of that pair being stitched together along a line closely adjacent the extremities of the wings so that the lap has a free end, the free end being movable to permit access through the gap to the associated device.

8. A cover for a bed-forming structure, wherein such structure includes at least one device accessible at the outside face of such structure, the cover comprising a plurality of panels to define top, bottom, end and side walls, the panels being dimensioned and being assembled with each other to be substantially coextensive with the outside walls of such structure, one of the panels, when the cover is assembled upon the structure, being juxtaposed to the device, the last mentioned panel including a pair of sections, the end of one of the sections of that pair being cut away in part to leave a pair of wings extending therefrom and having a gap therebetween, the sections of that pair being positioned one upon the other so that the other section of the pair forms a lap extending at least to the innermost extremities of the wings, and the sections of that pair being stitched together along a line closely adjacent the extremities of the wings so that the lap has a free end, the free end being movable to permit access through the gap to the associated device, and means carried by the lap and wings for retaining the lap in closing position with relation to the gap.

9. A cover for a bed-forming structure, wherein such structure includes at least one device accessible at the outside face of such structure, the cover comprising a plurality of panels dimensioned and being assembled with each other to be substantially coextensive with the outside walls of such structure, one of the panels, when the cover is assembled upon the structure, being juxtaposed to the device, the last mentioned panel including a pair of sections, the end of one of the sections of that pair being cut away in part to leave a pair of wings extending therefrom and having a gap therebetween, the sections of that pair being positioned one upon the other so that the other section of the pair forms a lap extending at least to the innermost extremities of the wings, and the sections of that pair being stitched together along a line closely adjacent the extremities of the wings so that the lap has a free end, the free end being movable to permit access through the gap to the associated device, and means carried by the lap and wings for retaining the lap in closing position with relation to the gap.

sioned and assembled with each other to be substantially coextensive with the outside walls of such structure, one of the panels including a plurality of sections, one of the sections of that panel having a cut-out formed therein, the sections being greater in their total length than the length of the panel, the sections of that panel being overlapped sufficiently to coincide with the length of the panel and so that the cut-out is overlapped by one of the other sections of that panel, and the sections of that panel being secured to each other so that a portion of said other section forms a freely movable cover for the cut-out.
